UNITED STATES PATENT OFFICE.

BELA BOGNAR, OF NEW YORK, N. Y.

PERMANENT-HAIR-WAVING DEVICE.

Application filed September 11, 1926. Serial No. 134,852.

The present invention relates to improvements in permanent hair waving devices, and more particularly to means for supporting the heating elements thereof.

5 Modern hair wavers are usually operated by electricity, the heating elements being supported by means of their flexible electric wires, provided with attachment plugs which co-operate with sockets or receptacles 10 on a chandelier, the latter being usually attached to the ceiling of the room in which the hair waving apparatus is located. These devices are objectionable for several reasons. First of all, the chandelier, which must project down into the room a distance so that the electric plugs can be easily connected and disconnected with their co-operating elements, obstructs passage through the working room even when not in use. Furthermore, the chandeliers are permanently attached to the ceiling of the room, so that, unless the person whose hair is to be treated sits close by, the operation becomes rather difficult.

25 The main object of the present invention is to provide a permanent hair waver, the heating elements of which are carried by a portable support, which may be placed into a corner of the room when not in use and 30 which may be shifted to any desired location in relation to the person, whose hair is being treated, before and during the treatment.

With these and other objects in view, 35 which will more fully appear as the nature of the invention is better understood, the same consists in the combination, arrangement and construction of parts hereinafter described, pointed out in the appended 40 claim and illustrated in the accompanying drawings, it being understood that many changes may be made in the size and proportion of the several parts and details of construction within the scope of the appended claim, without departing from the spirit 45 or sacrificing any of the advantages of the invention.

One of the many possible embodiments of the invention is illustrated in the accompanying drawings, in which:—

Figure 1 is a side elevation of a permanent hair waver constructed in accordance with the present invention; and Fig. 2 is a top plan view thereof.

55 In the drawings, the numeral 10 indicates a standard, mounted upon legs 11. The up-

per portion of this standard is tubular and is adapted to receive a support 12, including a vertically extending cylindrical bar portion 13, fitting into the tubular portion of the standard 10, and an outwardly extending horizontal portion 14, terminating in a downwardly extending section 15. This support is shiftable on the standard, a set screw 10' serving to fix the support on the standard in any desired position. The support is shiftable vertically on the standard and may also be turned on the standard, so as to bring the heating elements, hereinafter to be described, in any desired position in relation to the person to be treated. To the section 15 of the support is attached in any suitable manner a ring-shaped member 16, on which are mounted electric sockets 17, connected by wires 18 with an outlet box, not shown, for supplying electric current to the heaters. Into each of the sockets is adapted to be fitted a plug 19, connected by flexible electric wires 20 with two heating elements 21. These heating elements may be of any suitable construction, for instance of the type described in an application for U. S. Letters Patent for improvements in electric heaters, filed by me on Feb. 16, 1926, Ser. No. 88,596.

To the section 15 of the support is furthermore attached, above the socket supporting member 16, a preferably, ring-shaped member 22, carrying a plurality of guides 23, for instance in the form of eyelets. Through each eyelet extends a flexible support 24, such as a cord, one end of which is attached to the wires 20 of a pair of heaters 21, while its other end extends into a housing 25, secured in any suitable manner to the portion 13 of the support 12. Each cord 24 has attached to it within the housing 25 a weight 26, by means of which the heating elements are counter-balanced and stay at whatever elevation they are put. Each cord 24 passes through a guide 27 on the top of the housing 25, said guides being, preferably, in the form of an eyelet. In this manner the weights 26 are separated or spaced within the housing. The guides 23 and 27 prevent the cords from becoming entangled and interfering with the electric wires 20, as the support 12 and the elements thereon are shifted on the standard 10 into the desired positions.

The apparatus is moved into proper relation to the chair occupied by the person

whose hair is to be treated. The support 12 and the elements carried thereby are then shifted on the standard 10 so as to bring the heaters above the head of the person, the 5 support being thereafter lowered or raised according to the requirements, after which the set screw 10' is turned to fix the support in the selected position. The strands of hair are then wound upon the core elements 10 of the heaters, the latter being raised or lowered according to the requirements and kept in the desired positions by the counter-weights, as above described. When the apparatus is not in use, it may be moved out 15 of the way into a corner or near to a wall of the room, so as not to interfere with the movement of the persons in the room.

What I claim is:—

20 A portable apparatus for waving hair, comprising a plurality of legs, a standard rising therefrom, the upper portion of said standard being tubular, a support including a vertical section and a sidewardly projecting horizontal section, said vertical section 25 being adapted to be telescoped into the tubular portion of said standard and being ro-

tatable thereon, means for fixing said support on said standard in any desired position, a housing secured to the vertical section of said support, a guide member on the 30 sidewardly extending section of said support, heating elements, cords attached to said heating elements in engagement with said guide member extending into said housing, a counter-balancing weight fixed to each 35 cord within said housing, said weights being disposed close to the vertical axis of the vertical section of said support, guides attached to said housing, said cords extending through said last-mentioned guides and the 40 said last-mentioned guides serving also for spacing said weights, an electric-socket carrying member on the sidewardly projecting section of said support, and electrical connections extending from said heating members to the sockets on said socket carrying member.

Signed at New York, in the county of New York, and State of New York, this 8th day of September, A. D. 1926.

BELA BOGNAR.
